TWO-CYCLE ENGINE

Benjamin Kahn, New York, N. Y.

Application April 17, 1933, Serial No. 666,418

28 Claims. (Cl. 123—53)

This invention relates to improvements in two-stroke cycle internal combustion engines of the "opposed piston" type having substantially "straight-thru" or "end-to-end" scavenging effect.

One of the objects of the invention is to provide a compact engine of this type.

Another object is to provide an engine of the above character with the minimum number of 10 crankshaft throws per piston section.

The principle feature of the invention consists in angularly relating the "end-to-end" cylinders and further consists in offsetting the "end-to-end" cylinders to effect the compactness of the 15 engine and the simplicity of its crank train.

In the drawing, forming part of this disclosure, the illustrations show the principle of the invention, it being understood that various changes may be made without departing from the spirit 20 of the invention as set forth in the appended claims.

Figure 1 is a transverse sectional view of a single cylinder engine constructed in accordance with the invention and illustrating the angulated relationship of the pistons.

Figure 2 is a similar sectional view of obtuse V-type engine constructed in accordance with the engine shown in Fig. 1.

Figure 3 is a similar view of a "diamond" 30 shaped engine constructed in accordance with the engine shown in Fig. 1.

Figure 4 is a longitudinal section of a modified form of the engine shown in Fig. 3.

In the form of the engine illustrated in Fig. 1 35 a crankcase 10 is provided with a cylinder block having a bore 11 and a crosshead bore 12. An intake piston 13 is adapted to operate in bore 11 and is suitably connected to a crankshaft 14 by means of a connecting rod 15. A crosshead 16 40 is adapted to operate in the bore 12 and is suitably connected to a crankshaft 17 by means of a connecting rod 18. In order to counteract torque reaction of the engine, both crankshafts are adapted to rotate at the same speed, and 45 opposite directions to each other. This may be accomplished by gears 19 and 20. In conjunction with suitable counterweights on the shafts the torque reactions are counteracted.

A cylinder head 21 is secured to the cylinder 50 block and is provided with a bore 22. An exhaust piston 23 is adapted to operate in said bore and is secured to the crosshead 16 by means of tie rods 25 on both sides of the exhaust piston and crosshead. These tie rods are disposed 55 behind each other, lengthwise of the engine. These

rods are arranged outside of the combustion chamber, and lie above the intake pistons and within the projecting space required by the intake piston between confining planes of the space required by said intake piston lengthwise of the 5 engine. In other words, the space required lengthwise of the engine to accommodate these tie rods one group behind another, is less than the space required by the intake pistons one behind another lengthwise of the engine. This in 10 effect allows a minimum engine length for a plurality of intake pistons of a given diameter. For example, in a four-in-line engine of 5 ins. intake piston diameter, the length of the engine would be about 24 ins. including slight space between 15 cylinders. It is intended that the tie rods connecting the exhaust pistons 23 with their cross-heads 16 should not be more than 5 ins. which leaves sufficient space between each pair of tie rods to allow for an exhaust piston of ample 20 diameter so as not to restrict the exhaust port capacity.

A cover 26 is secured to the cylinder head 21 to enclose the exhaust piston. An oil pan 27 forms a bottom closure for the crankcase 10.

Intake ports 28 are suitably arranged around the cylinder bore 11 and are controlled by the intake piston. Exhaust ports 29 surround the exhaust cylinder bores 22 and are controlled by the 25 exhaust piston 23.

The exhaust piston and its associated parts are arranged in alignment but are angularly disposed with respect to the alignment of the intake piston and are offset therefrom.

This angular offset of the exhaust piston and its associated parts permits the exhaust piston to lie substantially over the intake piston to effect substantially "straight-thru" scavenging and further permits the tie rods to pass downwardly and alongside the intake piston within the projected 35 space of the intake cylinder. This arrangement of extending the exhaust crank train substantially downwardly minimizes the height of the engine, and the disposition of the crank train substantially alongside the intake cylinder requires 40 no additional space longitudinally of a multi-cylinder engine; thereby minimizing the length 45 thereof.

Figure 2 shows the application of the invention to form a V type engine. An exhaust crankshaft 50 17a, similar to the crankshaft 17 but having two throws one for each exhaust piston, is adapted to operate two exhaust pistons in a manner heretofore described.

A single crankshaft 14a similar to the crank- 55

shaft 14 is adapted to operate two intake pistons in the same manner as described in Fig. 1.

Figure 3 shows the application of the invention shown in Fig. 2 in multiple forms, to provide a 5 "diamond" shape engine.

An exhaust crankshaft 17b similar to the crankshaft 17a of Fig. 2, is adapted to operate the exhaust pistons in a similar manner. Two intake piston operating crankshafts 14b are arranged on opposite sides of the crankshaft 17b. Each of these intake crankshafts are adapted to operate two intake pistons 13 which are obtusely disposed as indicated at X in the manner described in Figure 2. With this construction an 10 engine is formed having two combustion groups each having one combustion chamber for each group common to two combustion groups each having two intake pistons and one exhaust piston.

Figure 4 is a modified form of the engine shown 20 in Fig. 3. Instead of using three individual crankshafts, a single crankshaft 35 has been substituted which necessitated the enlargement of the included angle X to 180 degrees normal with the cylinder axes to the crankshaft.

Having thus described the invention, what is 25 claimed as new and desired to secure by Letters Patent, is:—

1. A two-stroke cycle internal combustion engine comprising a plurality of power units, each 30 having U type cylinder, a single combustion chamber communicating therewith, a cylinder communicating with said combustion chamber in opposed relation to said U type cylinder, pistons adapted to operate in the cylinders, and 35 crank throws for each of the pistons arranged on the same side of the combustion chamber.

2. An internal combustion engine having in 40 combination, a plurality of power units, each power unit having a U type cylinder including a combustion chamber, pistons adapted to move in substantially parallel unison in the legs of the U type cylinder, and piston means in communication with said combustion chamber adapted to move substantially opposite to said pistons in 45 said U type cylinder.

3. An internal combustion engine having in 50 combination, a plurality of power units, each power unit having a U type cylinder including a combustion chamber, pistons adapted to move in unison in said U type cylinder, piston means in communication with said combustion chamber adapted to oppose said pistons in said U type cylinder, and a single crank shaft cooperating with all of said pistons.

4. An internal combustion engine having in 55 combination, a plurality of power units, each power unit having a U type cylinder including a combustion chamber, pistons adapted to move in unison in said U type cylinder, piston means in communication with said combustion chamber adapted to move opposite to said pistons in said U type cylinder, and a single crank throw for the 60 piston means adapted to oppose the pistons in the U type cylinder.

5. In a two-stroke cycle internal combustion 65 engine, the combination including a single combustion chamber, angularly disposed and substantially oppositely moving intake and exhaust controlling pistons commonly communicative with the combustion chamber, operably connected crank means, and separate connecting means independently operable between each piston and its crank means, whereby the intake piston connecting means is under compression and the 70 exhaust piston connecting means is under tension

during the expansion stroke of the engine, said exhaust piston connecting means including a pair of tie rods disposed side by side lengthwise of the engine, outside of the combustion chamber, to one side of the engine, and within the projected 5 space required by the intake piston, lengthwise of the engine.

6. A two-stroke cycle internal combustion engine of substantially "straight thru" scavenging type including substantially opposed intake and 10 exhaust cylinders, a single combustion chamber, substantially oppositely moving intake and exhaust pistons commonly communicative with the combustion chamber and operable in the cylinders, and a cylinder head, said cylinders being angularly disposed to each other, one of said piston means operable in said cylinder head.

7. A two-stroke cycle internal combustion engine including substantially opposed intake and 20 exhaust cylinders, a cylinder block, an associated cylinder head having ports, intake port controlling piston means operable in said cylinder block, exhaust port controlling piston means in said cylinder head, said piston means being adapted to move substantially oppositely, and connecting rod 25 means for the exhaust piston means including tie-rods outside the combustion chamber and the exhaust piston and within the projected space of the intake piston means lengthwise of the engine.

8. In a two-stroke cycle internal combustion 30 engine of substantially "straight thru" scavenging type the combination including substantially opposed cylinders, an intake controlling piston in one of the cylinders, over-head exhaust piston-valve means in the other of said cylinders, said 35 piston-valve means being angularly disposed and substantially opposite in movement to said intake piston, and a crank for the exhaust valve means disposed in the projected path of the exhaust valve means during its compression stroke.

9. A two-stroke cycle internal combustion engine including a single common combustion chamber, three opposed port controlling piston means, a cylinder head, one of said piston means adapted to control exhaust ports operable in said head, 45 and operable connecting means for said exhaust piston outside of the combustion chamber and within the projected space of the intake pistons lengthwise of the engine.

10. A two-stroke cycle internal combustion 50 engine including a plurality of power units, each power unit having a single combustion chamber, intake and exhaust controlling piston means commonly communicative in the combustion chamber, and crank throws associated respectively with each of said piston means, said exhaust pistons adapted to move away and said intake piston means adapted to move toward their respective crank throws during the expansion stroke, a crank shaft associated with all the intake piston means, and all exhaust piston means being connected to another crankshaft, said crankshafts being operably interconnected and adapted to rotate oppositely.

11. An internal combustion engine including a 55 crankshaft, a single combustion chamber, a plurality of cylinders communicating with said combustion chamber and disposed between the combustion chamber and the crankshaft, a cylinder 70 communicating with said combustion chamber remote of the crankshaft, pistons in said cylinders, and connecting means for the piston in the remote cylinder including the rods outside of the combustion chamber and within the projected 75

space of the first mentioned cylinders lengthwise of the engine.

12. A two-stroke cycle internal combustion engine including substantially opposed intake and exhaust cylinders, intake and exhaust piston means adapted to operate in said cylinders, a single connecting means associated with each of said piston means, and a single crank throw for each of said connecting means, the intake piston means adapted to move toward and the exhaust piston means adapted to move away from their respective connecting means during the expansion stroke, said connecting means for the exhaust piston including means within the projected space of the intake cylinder lengthwise of the engine and outside the exhaust cylinder.

13. A two-stroke cycle internal combustion engine including a plurality of power units, each of said power units having opposed intake and exhaust cylinders, intake and exhaust piston means adapted to operate in said cylinders, separate connecting means associated with each of said piston means, the intake piston means of each unit adapted to move toward and the exhaust piston means adapted to move away from their respective connecting means during the expansion stroke of the power unit, a single crank throw for all piston means adapted to move toward, and a single crank throw for all piston means adapted to move away from their respective connecting means during the expansion stroke of the respective units, said connecting means for the exhaust piston including means within the projected space of the intake pistons lengthwise of the engine and outside the projected space of the exhaust pistons.

14. A two-stroke cycle internal combustion engine having a single combustion chamber, intake and exhaust pistons commonly communicative with the combustion chamber, a single crank throw for each of the pistons, the intake piston adapted to move toward and the exhaust piston adapted to move away from their respective crank throws during the expansion stroke of the engine, and tie rods operatively associated with said exhaust piston and arranged within the lengthwise confining parallel planes of the intake piston, said tie rods extending to and connecting at the open end of the exhaust piston.

15. A two-stroke cycle internal combustion engine including a piston, a head, an over-head piston-valve, a single individual crankshaft for said piston, another single individual crankshaft for said piston-valve, said piston-valve adapted to move away from its crankshaft during the expansion stroke of the engine, and connecting means for the piston-valve in line with the axis of the piston-valve.

16. A two-stroke cycle internal combustion engine including a plurality of power units each having a piston, and an over-head piston-valve, a crankshaft in the engine to operate all of the said pistons, and another crankshaft for all of said piston-valves of the engine, said piston-valves adapted to move away from their crankshaft during the expansion stroke of the engine.

17. A two-stroke cycle internal combustion engine including a single combustion chamber, three parallel pistons commonly communicative with said combustion chamber, and a cylinder head, one of said piston means operable in said head and adapted to move opposite the other two.

18. A two-stroke cycle internal combustion engine including a single combustion chamber, three

parallel pistons commonly communicative with said combustion chamber, a cylinder head and a crank throw for each of said pistons, one of said pistons operable in said head and adapted to move away from its crank throw during the expansion stroke of the engine.

19. In a two-stroke cycle internal combustion engine, the combination including substantially opposed cylinders, a single combustion chamber commonly communicative with the cylinders, substantially oppositely moving intake and exhaust controlling pistons in the cylinders, a single crank-throw for each of the pistons in line with their respective pistons, working faces on the pistons entirely exposed to the combustion chamber during maximum compression of the engine, and means whereby the intake controlling piston moves toward and the exhaust controlling piston moves away from its respective crank-throw during the expansion stroke of the engine.

20. In a two-stroke cycle internal combustion engine, the combination including angularly disposed cylinders, a single combustion chamber commonly communicative with the cylinders, intake and exhaust controlling pistons in the cylinders, a single crank-throw for each of the pistons in line with their respective pistons, working faces on the pistons entirely exposed to the combustion chamber during maximum compression of the engine, and means whereby the exhaust controlling piston moves away from its crank-throw during the expansion stroke thereof.

21. In a two-stroke cycle internal combustion engine, the combination including a crankshaft, a single combustion chamber, a plurality of cylinders commonly communicative with the combustion chamber, a plurality of intake pistons in the cylinders, an exhaust piston working in one of the cylinders substantially opposite in direction to the pistons in the intake cylinders, a single crank-throw on the crankshaft cooperating with the exhaust piston, and means whereby the exhaust piston moves away from its crank-throw during the expansion stroke of the engine.

22. In a two-stroke cycle internal combustion engine, the combination including angularly disposed and substantially opposed cylinders, intake and exhaust pistons in the cylinders, a single crank-throw for the piston in the exhaust cylinder, and means whereby said piston moves away from its crank-throw during the expansion stroke of the engine.

23. In a two-stroke cycle internal combustion engine of the substantially straight-thru scavenging type, the combination of substantially opposite moving pistons communicative with a single combustion chamber, a single crank-throw crankshaft for each of the pistons, said crank-throws substantially adjacent to each other, and means connecting the crankshafts whereby they are caused to rotate at equal speed and in opposite directions, thereby counteracting their torque reactions on the engine of the moving parts associated with the crankshafts.

24. In a two-stroke cycle internal combustion engine, the combination including an intake piston, an exhaust piston, said pistons adapted to move substantially oppositely and adapted to communicate with a single combustion chamber, a single crankpin for the intake piston, a single crankpin for the exhaust piston substantially in the extended axis of the exhaust piston, said exhaust piston adapted to move away and said intake piston adapted to move toward their respective crankpins during the expansion stroke of

the engine, and connecting means including a connecting rod between the exhaust piston and its crankpin, said connecting means being disposed substantially symmetrically along the axis of the 5 exhaust piston.

25. In an internal combustion engine the combination of an intake-controlling and power-contributing piston, an exhaust-controlling and power-contributing piston, said pistons having 10 closed ends commonly communicative with a single combustion chamber, a crankshaft, a connecting rod for the intake piston, means cooperating with the exhaust piston including a second crankshaft parallel to the first mentioned 15 crankshaft and having its axis coplanar with the axis of the exhaust piston, a crosshead, a connecting rod between the crosshead and the second crankshaft, and tie rods between the crosshead and the open end of the exhaust piston, said tie 20 rod extending from the open end of the exhaust piston in the direction of the closed end of the exhaust piston, said connecting rod for the exhaust piston being disposed alongside the intake piston.
- 25 26. In a two-stroke cycle internal combustion engine, the combination including a single combustion chamber, oppositely moving intake and exhaust controlling pistons commonly communicative with the combustion chamber, a single 30 crank-throw for each of the pistons in line with their respective pistons, and means whereby the intake piston moves toward and the exhaust piston away from their respective crank-throws during the expansion stroke of the engine, said 35 means including connecting means between the exhaust piston and its crank-throw, said connecting means being disposed outside the combustion chamber substantially on one side of the engine

and confined within a space smaller than the projected space of the intake piston.

27. In a two-stroke cycle internal combustion engine, the combination including a single combustion chamber, substantially oppositely moving intake and exhaust controlling pistons offset with respect to each other and commonly communicative with said combustion chamber, a single individual crank-throw for each of said pistons in line with their respective pistons, and means 10 whereby the intake piston moves toward and the exhaust piston away from their respective crank-throw during the expansion stroke of the engine, said means including connecting means between the exhaust piston and its crank-throw, said connecting means being disposed outside the combustion chamber substantially on one side of the engine and within the projected space of the intake piston. 15

28. In a two-stroke cycle internal combustion 20 engine, the combination including a single combustion chamber, angularly disposed and substantially oppositely moving intake and exhaust controlling pistons commonly communicative with the combustion chamber, operably connected crank means in line with and independently connected with one of said pistons, the intake piston being disposed between its crank means and the combustion chamber and the exhaust piston being disposed adjacent the combustion chamber and remote of its crank means, and connecting means for the exhaust piston disposed outside of the combustion chamber, substantially to one side thereof, and within the longitudinal projected space of the engine required by the intake piston. 25 30 35
